US00D864140S

(12) **United States Design Patent** (10) **Patent No.:** **US D864,140 S**
(45) **Date of Patent:** **** Oct. 22, 2019**

(54) **MOBILE PHONE**

(71) Applicant: **Guangdong Oppo Mobile Telecommunications Corp., Ltd.,**
Dongguan, Guangdong (CN)

(72) Inventor: **Yuxian Lin**, Guangdong (CN)

(73) Assignee: **Guangdong Oppo Mobile Telecommunications Corp., Ltd.,**
Dongguan (CN)

(**) Term: **15 Years**

(21) Appl. No.: **29/630,560**

(22) Filed: **Dec. 21, 2017**

(30) **Foreign Application Priority Data**

Jun. 28, 2017 (CN) 2017 3 0276646

(51) **LOC (12) Cl.** **14-03**

(52) **U.S. Cl.**

USPC ..... **D14/138 G**

(58) **Field of Classification Search**

USPC ..... D14/138 G, 138 AD, 341, 138 R, 496,
D14/203.1, 203.3, 203.5, 203.7, 248;
455/575.1, 556.2; D21/517, 329;

(57) **CLAIM**

The ornamental design for a mobile phone, as shown and
described.

DESCRIPTION

FIG. 1 is a front view of the mobile phone showing my new
design.

FIG. 2 is a rear view of the mobile phone of FIG. 1.

FIG. 3 is a left side view of the mobile phone of FIG. 1.

FIG. 4 is a right side view of the mobile phone of FIG. 1.

FIG. 5 is a top view of the mobile phone of FIG. 1.

FIG. 6 is a bottom view of the mobile phone of FIG. 1.

FIG. 7 is a top, front perspective view of the mobile phone
of FIG. 1.

FIG. 8 is a bottom, front perspective view of the mobile
phone of FIG. 1.

FIG. 9 is a left, rear perspective view of the mobile phone
of FIG. 1; and,

FIG. 10 is a right, rear perspective view of the mobile phone
of FIG. 1.

The shade lines in the figures show contour and not surface
ornamentation.

The oblique shade lines in the figures show transparency or
translucency.

1 Claim, 9 Drawing Sheets
